UNITED STATES PATENT OFFICE

FRANK H. RYDER, OF COBLESKILL, NEW YORK, ASSIGNOR TO HARDER REFRIGERATOR CORPORATION, A CORPORATION OF NEW YORK

REFRIGERATOR

Application filed March 1, 1929. Serial No. 343,590.

My invention is particularly directed to an improved construction of ice refrigerators. The invention contemplates a construction in which provision is made for collecting and draining any moisture condensed on the outer surface of the metallic ice chamber wall between the ice chamber wall and the refrigerator wall.

In refrigerator constructions, it is the general practice to form the back, side walls and pan of the ice chamber in a unitary structure. This is sometimes done, for example, by forming the rear wall and the bottom or pan member from a single piece of galvanized sheet iron with their edges flanged and overlapping the sides which are separate members suitably secured in place, the front edge of the bottom being finally turned up and secured to complete the pan. In the assembled refrigerator, the one side wall and the back wall are in direct contact with the composite wall of the refrigerator, usually there being interposed a layer of water-proof paper or similar material.

Usually, the refrigerator wall is composed of wood with a lining of cork-board or other suitable heat insulating material, and the water-proof paper on both sides of the lining. Despite the use of the water-proof paper within the refrigerator wall, gaseous moisture permeates through the wall and is condensed on the outer surfaces of the ice chamber wall. The water so condensed collects between the ice chamber wall and the refrigerator wall. This water of condensation is more or less absorbed by the wooden wall, and the swelling which results therefrom frequently assumes destructive proportions.

One of the purposes of my invention is to prevent this absorption of the moisture of condensation by the wooden walls of the refrigerator. One way contemplated by my invention to accomplish this is to space the metallic ice chamber wall from the wooden refrigerator wall with its water-proof lining. While this may be done in various ways, I have found it satisfactory to utilize spaced strips of wood or other material of small heat conductive capacity, like furring strips, be-

tween the metal and wooden walls for the purpose.

My invention also comprehends means to dispose of this water of condensation, and this may be done by providing a construction in which the water condensed on the outer surface of the ice chamber wall has a free passage to the refrigerator drain. For example, the parts may be so designed that the ice chamber walls are contained within and drain into the ice pan, in which case the ice pan is structurally separate from the side walls of the ice chamber.

A detailed description of one embodiment of my invention will be given in connection with the accompanying drawings in which:

Fig. 1 is a perspective of a refrigerator having parts broken away to show the construction of the ice chamber and adjacent wall section;

Fig. 2 is a vertical section through the refrigerator on the line 2-2 of Figure 1, and

Fig. 3 is a horizontal section on the line 3-3 of Figure 2.

In the embodiment illustrated, the composite refrigerator wall 1 consists of an outer wooden wall section 2, and a cork-board lining 3 which is wrapped in water-proof paper 4. Strips or cleats 5 are interposed against and secured to the inner face of the composite refrigerator wall and serve positively to maintain a space between the ice chamber and the refrigerator wall. The strips 5 are nailed or otherwise secured to the upper and lower cross pieces 6. The metallic ice chamber 7 is placed in the refrigerator with the rear wall 8 against the strips 5 on the rear wall of the refrigerator and the side wall 9 against the end wall 10. The rear wall 8 and the side wall 9 slope inwardly from the strips 5 from the top downwardly as will be hereinafter described.

The ice chamber 7 is constructed by bending a single piece of galvanized sheet iron to form the back 8 and sides 9, 11. To form the bottom or ice pan 12, the edges of a piece of galvanized sheet iron, cut to the proper proportions, are bent upwards to form an obtuse angle therewith and constitute sloping sides therefor. The joints at the corners 100

formed by the turned-up edges or sides are suitably closed in a water-tight manner. The sides 13, 14 of the pan 12 are provided with bends 15 to receive the strips 5 on the refrigerator wall. The walls of the ice chamber sit within the pan 12, the bottom of the walls being received within the sloping sides of the pan so that all drainage is caught by the pan. Due to the rearward inclination of the ice pan, which is necessary for proper drainage, the sides of the ice chamber are in contact with the bottom of the pan at the front only thereof as clearly shown in the drawing. Along the side 9 and rear 8, the walls are in contact with the sides of the ice pan only at the bends 15. Thus, there is a clear passage under the ice chamber wall to the refrigerator drain 16.

The ice pan 12 is placed in the refrigerator, and supported by the wooden ice bottom 17 provided therefor. The metallic walls are secured at their upper portion to the strips 5 where strips are used and to the upper cross member in the absence of strips. From the point at which they are secured, the walls slope away from the strips to enter the ice pan at their lower edge. Consequently, the metallic ice chamber walls are in contact with the strips or refrigerator wall only for a short distance at the upper portion thereof where condensation is negligible.

From the foregoing description, it will be apparent that any water condensing on the outer surface of the metallic walls will flow downward along the surface of the wall to the side of the ice pan and under the wall to the refrigerator drain.

It is obvious that various changes may be made in the construction shown in the drawings and above particularly described within the principle and scope of my invention as expressed in the appended claims.

I claim:

1. A refrigerator comprising a wall including a heat insulated lining absorptive to moisture, vertical spacing strips secured to the inner face of the wall, a drip pan for the ice chamber having the side wall adjacent said lining sloping outwardly into contiguity with the spacing strips, and a metallic chamber wall supported at its top against the spacing strips and sloping inwardly toward its bottom away from the strips and resting with its bottom edge upon the said inclined side wall of the drip pan.

2. A refrigerator comprising a wall including a heat insulated lining absorptive to moisture, vertical spacing strips secured to the inner face of the wall, a drip pan for the ice chamber having the side wall adjacent said lining sloping outwardly into contiguity with the spacing strips, and a metallic chamber wall supported at its top against the spacing strips and sloping inwardly toward its bottom away from the strips and resting

with its bottom edge upon the said inclined side wall of the drip pan, the line of contact of the bottom edge of the metallic ice chamber wall on the said inclined wall of the drip pan being broken at spaced intervals to form passages under the bottom edge of the metallic ice chamber wall.

3. A refrigerator comprising a wall including a heat insulated lining absorptive to moisture, vertical spacing strips secured to the inner face of the wall, a drip pan for the ice chamber having the side wall adjacent said lining sloping outwardly into contiguity with the spacing strips, and a metallic chamber wall supported at its top against the spacing strips and sloping inwardly at its bottom away from the strips and resting with its bottom edge upon the said inclined side wall of the drip pan, the said inclined side walls of the drip pan being bent around the spacing strips to form passages under the bottom edge of the metallic ice chamber wall.

In witness whereof, I hereunto subscribe my signature.

FRANK H. RYDER.
